UNITED STATES PATENT OFFICE.

ARTHUR LEE LIGON, OF FORT STOCKTON, TEXAS.

COUPLING CONNECTION FOR PUMP RODS.

Application filed June 28, 1924. Serial No. 722,996.

My invention relates to improvements in coupling connections for pump rods, and it consists in the combinations, constructions and arrangements herein described and claimed.

An object of the invention is to provide a connection which is adapted to be attached to the upper end of a pump or sucker rod and which then is adapted to be releasably secured to a vertically reciprocable part of the windmill, whereby the pump or sucker rod can be operatively connected with the driving mechanism of the windmill.

A further object of the invention is to provide a coupling connection of the character described which can be secured to a driving part of either a windmill or a pumping jack quickly and easily without the use of any special tools or unusual skill with but little time and labor and as quickly and easily detached from the driving part of the windmill or pumping jack.

A further object of the invention is to provide a coupling connection of the character described which comprises elements engaged adjustably with each other so that the effective length of the pump rod can be varied.

Other objects and advantages will be apparent from the following description, considered in conjunction with the accompanying drawings, in which—

Figure 1 is a fragmentary view, partly in vertical section and partly in side elevation, showing the coupling connection attached to the upper end of a pump rod and connecting the pump rod with the vertically reciprocable part of the driving mechanism of a windmill.

Figure 2 is a side elevation of the coupling connection and the associated parts at the opposite ends of the coupling connection, the view being taken at right angles to Figure 1.

Figure 3 is a fragmentary detail view, partly in side elevation and partly in vertical section, showing the manner of attaching separable elements of the connection together.

Figure 4 is a side elevation, showing the upper coupling member of the connection connected with a vertically reciprocable part of the windmill driving mechanism.

Figure 5 is a perspective view showing a portion of the structure exhibited in Figure 4, and

Figure 6 is a perspective view of the ring for releasably holding the jaws of the structure shown in Figure 4 closed.

Referring now to the drawings and particularly to Figure 1 thereof, the numeral 1 designates the upper end portion of a well casing and 2 is the upper end portion of a pump or sucker rod which is vertically reciprocable in the well casing. A coupling connection embodying the invention comprises a rod 3 which is provided with screw threads extending from the upper end thereof for the greater part of its length as indicated at 4 and is connected by a union 5 to the pump or sucker rod 2, being held rigid with the pump or sucker rod in axial alignment with the latter and constituting what may be considered the upper end portion of the pump or sucker rod. A thimble 6 surrounding the rod 3 is joined integrally or otherwise to a flanged adjusting nut 7 which is in engagement with the threads 4. The thimble 6 will be moved vertically of the rod 3 when the nut 7 is turned in engagement with the threads 4. The thimble 6 is at the lower end of the nut 7 and the flange on the nut 7, indicated at 8, is at the upper end of the thimble. A jam nut 9 in engagement with the threads 4 of the rod 3 below the thimble 6 has a flange 10 at its upper end which will be positioned at the lower end of the thimble when the nut 9 has been turned until tight against the thimble 6. Obviously, the flanges 8 and 10 may be washers which were formed separately from the nut and associated with the latter.

A second jam nut 11 is in engagement with the threaded portion of the rod 3 above the nut 7 and has a flange 12 at its upper end. The nut 11 is counterbored at its upper end as shown at 13 in Figure 3, the counterbore opening through the upper face of the flange 12 and increasing in cross sectional area from its bottom toward its upper end. A jam nut 14 is in engagement with the threaded portion of the rod 3 above the nut 11 and is joined integrally or otherwise at its lower end to a thimble or sleeve 15 which surrounds the rod 3.

The sleeve or thimble 15 is best seen in Figure 1. A gripping device shown to advantage in Figures 1, 2 and 4 comprises a pair of arms 16 and 17 respectively pivotally connected together at their upper ends, as at 18 and having inwardly turned portions at their lower ends constituting co-

operating jaws indicated at 16^a and 17^a. The jaws 16^a and 17^a have vertical grooves in the confronting faces thereof as indicated at 19 in Figure 4 which are curved 5 transversely to conform to the curvature of the thimble 15, whereby the arms 16 and 17 may be swung from the position illustrated in Figure 4 until the thimble 15 is partially received in each of the grooves 19 and is 10 embraced by the jaws 16^a and 17^a. A retaining ring 20 may be slid downwardly on the arms 16 and 17 from the position shown in Figure 4 to the position shown in Figure 1 and will hold the arms against swinging 15 apart at their lower ends, whereby the jaws 16^a and 17^a will be held in embracing relation to the thimble 15 and the arms 16 and 17 then will be held against lateral movement relatively to the rod 3. The jaws 16^a 20 and 17^a have reduced tapering lower end portions adapted to enter the counterbore 13 of the jam nut 11 when the latter has been turned on the threaded portion of the rod to position to clamp the jaws 16^a and 17^a 25 against the thumb nut 14. The arms 16 and 17 thus will be held against longitudinal movement relatively to the rod and will be substantially rigid with the rod.

The arm 16 is provided with an offset axial 30 extension 21 at its upper end which is of rod-like formation and will be disposed in axial alignment with the rod 3 when the jaws 16^a and 17^a have been secured in embracing relation to the thimble 15 in the manner described. The rod-like extension 21 is joined by means of a coupling 22 or in any other suitable known manner to a connecting member 23 which may have forks 24 at its upper end adapted to straddle the lower end 40 of a windmill pump pole or like vertically reciprocable part of the driving mechanism of a windmill. The member 23 in actual practice is connected more or less permanently to the vertically reciprocable part of 45 the windmill driving mechanism and for the purpose of the disclosure of this invention may be termed a part of the driving mechanism of the windmill, since the member 23 forms no part of the coupling connection 50 which my invention provides and the rod extension 21 may be secured to any suitable vertically reciprocable part of the driving mechanism of a windmill through the agency of any suitable connecting member. With 55 the pump or sucker rod 2 connected with a vertically reciprocating part of the driving mechanism of a windmill, the pump or sucker rod 2 will be reciprocated vertically. In order to detach the reciprocating part of 60 the driving mechanism of the windmill from the rod 3 and thus to disconnect the driving mechanism of the windmill from the pump or sucker rod 2, it only is necessary to slide the ring 20 upward on the arms 16 and 17 65 and to loosen the jam nut 11 slightly so that

the arms 16 and 17 may be swung apart until the thimble 15 no longer is gripped between the jaws 16^a and 17^a. The ring 20 may be releasably held adjacent to the upper ends of the arms 16 and 17 through the agency of a 70 spring latching arm 25 which is disposed between the arms 16 and 17 and is connected at its lower end to the arm 16, the upper end portion of the latching member being bent laterally as indicated at 26 for engagement 75 with the ring 20 when the latter has been moved upward along the arms 16 and 17 to the position shown in Figure 4.

Obviously, my invention is susceptible of embodiment in forms other than that illustrated in the accompanying drawings and I therefore consider as my own all such modifications and adaptations of the form of the device herein described as fairly fall within the scope of the appended claims. 80

I claim:

1. A coupling attachment for a pump rod having a screw threaded upper end portion, comprising a sleeve surrounding the threaded portion of said extension, a nut 90 at the upper end of said sleeve in engagement with the threaded extension and connected with said sleeve, a second nut engageable with the threaded extension below said sleeve, said last named nut having a recess in the upper face thereof adapted to surround said extension, a pair of pivotally connected arms having jaws at the free ends thereof for cooperating with each other to grip said sleeve between said nuts, one of said arms having an extension attachable to a vertically reciprocating part 100 of the driving mechanism of a windmill, and means engageable with said arms for releasably holding said jaws in engagement 105 with said sleeve.

2. A coupling attachment for a pump rod having a screw threaded upper end portion, comprising a sleeve surrounding the threaded portion of said extension, a nut 110 at the upper end of said sleeve in engagement with the threaded extension and connected with said sleeve, a second nut engageable with the threaded extension below said sleeve, said last named nut having a recess in the upper part thereof adapted to surround said extension, a pair of pivotally connected arms having jaws at the free ends thereof for cooperating with each other to grip said sleeve between said nuts, one of said arms having an extension attachable to a vertically reciprocating part 115 of the driving mechanism of a windmill, a ring encircling said arms and slidably therealong to and from position to maintain 120 said jaws in gripping relation to said sleeve, and means on one of said arms engageable with said ring for releasably holding the ring out of position to maintain the jaws 125 in gripping engagement with said sleeve. 130

3. A coupling attachment for a pump rod having a screw threaded upper end portion, comprising a sleeve surrounding the threaded portion of said extension, a nut 5 at the upper end of said sleeve in engagement with the threaded extension and connected with said sleeve, a second nut engageable with the threaded extension below said sleeve, said last named nut having 10 a recess in the upper part thereof adapted to surround said extension, a pair of pivotally connected arms having jaws at the free ends thereof for cooperating with each other to grip said sleeve between said nuts,

one of said arms having an extension at 15 tachable to a vertically reciprocating part of the driving mechanism of a windmill, a ring encircling said arms and slidable therealong to and from position to maintain said jaws in gripping relation to said sleeve, 20 said jaws having extensions adapted to enter the recess in the upper face of the second named nut when the jaws are in gripping relation to the sleeve and said second named nut has been screwed tight against the 25 lower end of said sleeve.

ARTHUR LEE LIGON.
